To all whom it may concern:

Be it known that I, Anna C. Flanagin, a citizen of the United States, residing at Bozeman, in the county of Gallatin and State of Montana, have invented a new, original, and ornamental Design for a Pillow Case, of which the following is a specification, reference being had to the accompanying drawing, forming part thereof.

The face of the pillow case opposite the face shown in the drawing is conventionally plain and unornamented.

I claim:

The ornamental design for a pillow case, as shown and described.
